(57) **CLAIM**

The ornamental design for a chair, as shown and described.

DESCRIPTION

FIG. 1 is a left side view showing my new design;
 FIG. 2 is a back side view thereof;
 FIG. 3 is a right side view thereof;
 FIG. 4 is a front side view thereof;
 FIG. 5 is a top view thereof;
 FIG. 6 is a bottom view thereof; and,
 FIG. 7 is a perspective view of the chair thereof.
 The broken-line oval placard is a portion of the chair which forms no part of the claimed design.
